IFilter filter Feb. 8, 2018 found on Jun. 14, 2021 at: <https://www.amazon.com/iFilters-Sediment-Comparable-Cartridges-Included/dp/B079NX153V/?th=1> (Year: 2018).*Primary Examiner — Jennifer Rivard*Assistant Examiner* — Jonathan E Fiencke(74) *Attorney, Agent, or Firm* — Foundation Law Group, LLP; Sevag Demirjian; J D Harriman(57) **CLAIM**

The ornamental design for a two stage filter, as shown and described.

DESCRIPTION

FIG. 1 is a top perspective view of a two stage filter according to my new design;

FIG. 2 is a bottom perspective view;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right-side view thereof.

The broken lines and areas within depict portions of the two stage filter that form no part of the claimed design.
